UNITED STATES PATENT OFFICE.

WALTER A. ABEgg, OF LOS ANGELES, CALIFORNIA.

SOCKET WRENCH.

1,422,067.

Specification of Letters Patent. Patented July 11, 1922.

Application filed December 15, 1920. Serial No. 430,877.

To all whom it may concern:

Be it known that I, WALTER A. ABEgg, a citizen of Switzerland, residing at Los Angeles, in the county of Los Angeles, State of

5 California, have invented new and useful Improvements in Socket Wrenches, of which the following is a specification.

This invention has to do with a wrench and more particularly with a socket wrench, 10 and an object of the invention is to provide an improved, simple and practical device of this character.

In using socket wrenches it is frequently necessary to use various sized sockets and 15 therefore to change the sockets on the shank. Further, it is necessary under certain circumstances to mount a socket solidly on the shank so that the wrench can be used in places where it is important that the socket 20 should not be lost or removed from the shank.

With the wrench provided by the present invention sockets can be placed on and removed from the shank by hand and without 25 performing any special operation, such as manipulating a catch or locking device, while at any time a socket can be solidly and rigidly set on a shank by manipulation of a single screw member. A socket can be easily and quickly set on the shank by hand to 30 be sufficiently solid for all ordinary use. When a socket is solidly set by operation of the positive locking means, it will not become dislodged under the most severe working 35 conditions.

A distinctive feature of the invention is the particularly simple, durable and effective structure which the invention provides for carrying out the above operations. The construction is not only simple, durable and effective, but is compact, simple and cheap of manufacture, and extremely simple and easy of operation. These features are of 40 particular importance commercially.

An important feature of the invention is the arrangement of parts which causes the socket to be effectively frictionally held on the shank when placed thereon without being positively set. The socket and shank are 45 actually held together by combined, frictional and wedging action. As provided by the invention, the frictional and wedging actions are adjustable to hold the shank and socket together with the desired degree of 50 firmness.

Another noteworthy feature of the inven-

tion is the construction which enables the shank and socket to be firmly and solidly locked together. Suitable manipulation of the screw, by which the above mentioned adjustments are made, causes the connection between the socket and shank to be both solid and positive. The mechanism employed in effecting this operation is extremely simple and cheap of manufacture and is equally 65 simple and easy of operation.

The various objects and features of the invention will be best and more fully understood from the following detailed description of a typical embodiment of the invention, throughout which reference is had to the accompanying drawings in which—

Fig. 1 is a side elevation of a wrench embodying the present invention showing a socket in place on the shank; Fig. 2 is a view 75 similar to Fig. 1 showing the socket in section and showing parts of the shank broken away to show its construction; the device in this figure being in its positively set position; Fig. 3 is a view similar to Fig. 2 showing the device set in position where the 80 socket can be easily placed on or removed from the shank by hand; Fig. 4 is an enlarged detail sectional view taken as indicated by line 4—4 on Fig. 2; and Fig. 5 is an 85 enlarged view of the shank showing it in the position shown in Fig. 3.

Throughout the drawings numeral 10 designates the shank of the wrench which may be of any suitable form or construction and which may be of any suitable length or size. In accordance with the present invention the end portion 11 of the shank 10, which is the portion that carries the socket 12, is non-circular in cross-sectional configuration. In 95 practice it has been found that the end portion 11 of the shank may be advantageously manufactured and operated if square in cross-sectional configuration. It is desirable, although not necessary, that the edges 100 13 of the end portion 11 be slightly beveled off in the manner shown in the drawings. In the particular wrench shown in the drawings, the body portion of the shank is round in cross-sectional configuration and the end 105 portion 11 is square in cross-sectional configuration, thus causing shoulders 14 to be formed where the two portions of the shank join. It is desirable that the shank be formed with shoulders, such as the shoulder 110 14, for reasons made obvious by the following description.

The socket 12, which is adapted to be mounted on the end portion 11 of the shank 10, is preferably formed of a solid or continuous block of steel and to have a recess 5 or opening 16 at one end and a recess or opening 17 at the other end. The recess 16 is of the same configuration as the end portion 11 of the shank and is adapted to receive the end portion of the shank. In practice it is preferred that the recess 16 be sufficiently large to receive the end portion 11 more or less freely. The clearance with which the end portion 11 of the shank 10 fits the recess 16 is shown in the drawing where it is somewhat exaggerated for purpose of illustration. The recesses 16 and 17 are independent of each other as far as function or operation is concerned, although they join and form a continuous passage 15 through the socket. The recess 17 is adapted to receive a nut, or the like, and is therefore usually made square or hexagonal in configuration and of such size as to fit standard sizes of bolts, nuts, etc. It will be understood, of course, how several or numerous 20 sockets 12 may be formed to have a standard size recess 16 to receive a standard size shank 10, but have different sized and shaped recesses 17 to receive or cooperate 25 with different sizes and shapes of nuts, bolts, etc.

In accordance with the present invention the end portion 11 of the shank is formed with an opening or hole 20 adapted to carry 30 a pressure member or ball 21. The hole 20 is formed or arranged in the end portion 11 so that the compression spring 22, arranged in the hole back of the ball 21 will thrust the ball 20 outwardly in the hole and against 35 the wall of the opening 16 in such manner as to wedge or press the end portion 11 of the shank into one of the corners of the recess 16. For instance, as shown in the drawings, the spring 22 presses or forces the ball 21 into one of the corners of the recess 16 and thereby causes the end portion 11 of the shank to be forced or wedged into the opposite corner of the recess. This causes two 40 sides or faces of the end portion 11 to be in frictional engagement with the walls of the recess 16 and also causes a wedging action. The frictional engagement of the parts of the end portion and the wedging action cause the shank and socket to be held together 45 firmly and effectively. The end portion 11 in being forced or wedged into one corner of the recess 16 prevents any looseness or play between the shank and socket such as might be caused by the looseness of fit 50 between the end portion 11 and the recess 16. In the practical construction of the device it is preferred that the hole 20 be formed diametrically through the end portion 11 and diagonally relative to the square 55 of the end portion 11.

The ball 21 is preferably a steel ball carried more or less loosely in the hole 20 and held against displacement from the hole 20 when the end portion 11 is removed from the recess 16, by the outer edge of the hole 20 being turned or beaded over at 23. It will be obvious, of course, that the effectiveness of the frictional engagement between the end portion 11 and the walls of the recess 16, and of the wedging action in holding the socket and shanks together, will depend upon the pressure or force with which the ball 21 is forced or pressed outwardly by the spring 22. In accordance with the present invention this pressure or force may be varied or adjusted by varying or adjusting the set screw 30 which screw-threads into the hole 20 and forms a seat for the inner end of the spring 22. It will be obvious how varying or adjusting the positioning of the set screw 30 in the hole 20 will vary or adjust the amount that the spring 22 is compressed and will thereby vary the pressure or force with which the spring 22 presses the ball 21. In the arrangement provided by the present invention the hole 20 extends completely through the end portion 11 so that the set screw 30 can be easily and conveniently adjusted from or through the end of the hole 20 opposite to that in which the ball 21 is arranged. It will be understood, of course, that set screw 30 may be formed with a suitable opening or slot 31 to receive a tool in order that the set screw may be turned or adjusted. It will be noted from inspection of the drawings that the set screw 30 is completely within the hole 20, thus allowing the shank to be easily placed in and removed from the recess 16.

In accordance with the present invention a block 33 is arranged in the hole 20 between the set screw 30 and the ball 21. When the spring 22 is a helical spring as shown in the drawings, the block 33 may be a solid metal block and may be arranged within the spring 22, as shown throughout the drawings. The block 33 is of such size or length that the set screw 30 can be adjusted to a position where the block 33 is positively forced against the ball 21, thereby causing the ball 21 to be positively forced into the corner of the recess 16. This action causes the end portion 11 to be positively forced or wedged into the corner of the recess 16, thus causing the shank and socket to be positively set or locked together. In the present disclosure of the invention. I have shown the block 33 as being independent of the ball 21 and also the set-screw 30 because I prefer to use a standard ball bearing ball for the ball 21 and a standard set screw for the set screw 30. Under this circumstance the block 33 may be a piece of heavy wire, or the like. This construction is obviously simple and extremely inexpensive.

In order that the set-screw 30 may be adjusted and manipulated when the socket 12 is in place on the end portion 11, an opening 36 is formed in the socket 12 to register with, or be opposite, the hole 20 when the socket is arranged on the shank, so that its upper end engages or seats against the shoulders 14. It is obvious, of course, that several holes might be formed in the socket 12 so that the set screw would be accessible regardless of the manner in which the end portion 11 might be arranged in the recess 16. However, in practice it is necessary to form only one opening 36 in the socket 12 as it is a very simple matter to arrange the shank in the socket so that the hole 20 registers with the opening 36.

In the operation of the device the set screw 30 is adjusted so that sockets 12 may be arranged on and removed from the end portion 11 of the shank by hand, yet to cause the sockets to be held on the end portion 11 with such firmness that they will not become displaced with ordinary usage of the wrench. 25 In other words, the set-screw 30 is adjusted so that sockets 12 may be interchanged by hand and be held in place on the shank with all ordinary necessary firmness. When it is desired to use the wrench under circumstances or in positions where it is absolutely essential that the socket should not become displaced from the shank, the set-screw 30 may be adjusted so that the ball 21 is positively forced into one corner of the recess 16, thus causing the end portion 11 to be positively forced or wedged into the opposite corner of the recess 16. When the device is set in this manner it may be used as a solid wrench and without danger of the socket 12 being displaced from the end portion 11. From the foregoing description it will be apparent that the invention may be easily and inexpensively constructed, that it is extremely simple and effective in operation, 45 that it is compact and neat, etc.

Having set forth only a typical embodiment of my invention, I do not wish to restrict myself to the specific details hereinabove set forth, but wish to reserve to myself any changes or variations that may appear to those skilled in the art or that may fall within the scope of the following claims.

Having described only a preferred form 55 of my invention, I claim:

1. In combination, a socket having a recess, a shank adapted to extend into the recess, and means adapted to be set to adjustably yieldingly hold the shank in the recess 60 or to positively hold the shank in the recess, said means comprising a pressure member, a spring adapted to press the pressure member when the shank is yieldingly held in the recess, a screw adapted to adjust the pressure 65 of the spring, and a part arranged to posi-

tively connect the pressure member and screw when the shank is positively held in the recess.

2. In combination a socket formed with a recess, a shank adapted to extend into the recess, and having an opening in the portion adapted to extend into the recess, a pressure member in the opening, a spring in the opening adapted to press the pressure member outwardly in the opening, a screw in the opening adapted to adjust the spring, and a part between the pressure member and the screw so that the screw can be adjusted to positively press the pressure member outwardly in the opening. 75

3. In combination, a socket formed with a recess, a shank adapted to extend into the recess and having an opening in the portion adapted to extend into the recess, a pressure member in the opening, means to prevent 85 displacement of the pressure member from the opening, a spring in the opening adapted to press the pressure member outwardly in the opening, a screw in the opening adapted to adjust the spring, and a block in the opening between the pressure member and the screw to form a positive connection between the pressure member and the screw upon certain adjustment of the screw. 90

4. In combination, a socket having a recess, a shank having a terminal adapted to extend into the recess, said end and recess being like and non-circular in cross section and said end having an opening through it with an end terminating at a point diametrically 100 opposite a corner of said shank terminal, a ball in the opening at said end, means to prevent displacement of the ball from the opening, a spring in the opening adapted to press the ball outwardly, a set screw in the opening adapted to regulate the spring, and a block between the set screw and the ball so that the set screw can be adjusted to positively move the ball outwardly in the opening, said socket having an opening adapted 110 to register with the opening in the shank when the shank is in place in the recess so that the set screw can be adjusted. 105

5. In combination, a socket with a substantially polygonal recess, a shank with a 115 similarly shaped terminal adapted to enter the recess, a transverse opening through the shank terminal terminating at one end at a corner of the shank terminal, a pressure member in and adapted to be projected from 120 that end of said opening, a spring behind said member, an adjusting screw behind the spring, and a block between the screw and pressure member through the medium of which block the screw may, when moved 125 toward the pressure member positively press it outwardly.

6. In combination, a socket with a shank receiving recess of substantially regular polygonal form, a shank with a terminal of 130

similar form adapted to enter the recess and having a transverse opening from corner to corner, a ball in one end of the opening and adapted to be projected therefrom, and 5 means to press the ball outwardly into engagement with a corner of the recess.

7. In combination, a socket with a shank receiving recess of substantially regular polygonal form, a shank with a terminal of 10 similar form adapted to enter the recess and having a transverse opening from corner to corner, a ball in one end of the opening and

adapted to be projected therefrom, a spring behind the ball, a screw behind the spring, and a block between the ball and screw 15 through the medium of which the ball may be positively forced outwardly by the screw.

In witness that I claim the foregoing I have hereunto subscribed my name this 10th day of December, 1920.

WALTER A. ABEGG.

Witness:

VIRGINIA BERINGER.
